[57] CLAIM

The ornamental design for a welding electrode storage canister, substantially as shown and described.

DESCRIPTION

FIG. 1 is a perspective view of a welding electrode storage canister showing our new design;
FIG. 2 is an elevational exploded view thereof, the opposite side being the same in appearance;
FIG. 3 is a top plan view thereof;
FIG. 4 is a bottom plan view thereof;
FIG. 5 is a cross-sectional view taken along line 5—5 of FIG. 2; and
FIG. 6 is a cross-sectional view taken along line 6—6 of FIG. 2.

FIG. 1.

FIG. 2.
